DRILLING MACHINE

Ernest A. Oakes, Elkins Park, Pa.

Application February 17, 1943, Serial No. 476,221

8 Claims. (Cl. 77—64)

This invention relates to drilling machines and more particularly to a drilling machine for drilling a multiplicity of openings in each of a multiplicity of turret fed objectives.

Specifically, the invention relates to a machine particularly adapted for use in drilling the flash openings in cartridge cases. These openings extend from the bottom of the percussion cap recess of the case base to the interior thereof and are so closely spaced that it is impractical to attempt simultaneous formation by the use of cluster drills. In the majority of instances, these openings are a diametrically spaced pair and are of very small size, particularly in the smaller case sizes such as the cases for shells utilized in airplane and anti-aircraft cannon. Due to the small diameter of the drills necessary to form these openings, it is essential that the exposed drill length be maintained at a minimum, that pressure be applied to the drill uniformly and that the drills be in high speed operation prior to any contact of the drill with the metal of the case. Again, due to the small size of the drills necessary, it is essential that some means be provided for automatically indicating the failure of any one of these drills since such small drills may readily break without any indication to the machine operator, particularly, where, as in the present instance, a fairly large gang of drills is in simultaneous operation.

Accordingly, a primary object of the present invention is the provision of means for drilling such openings which incorporates mechanism whereby the supported work and drills, one for each case being drilled, may be relatively accurately jogged, following an initial drilling operation on the case, to position the shell cases for the second drilling operation.

Another object of the invention is the provision of means for firmly holding the cases against possible circumferential displacement about their axes during those intervals in the drilling operation at which the drill is not actively engaged therewith.

Another object of the invention is to provide means for removing the cases from the supports upon which they are held during the drilling operation following the completion of such drilling operation, which means incorporates an apparatus for detecting the presence of an improperly drilled case and for halting the drilling operation until the case is removed.

A still further object is the provision of an apparatus incorporating a drilling halting mechanism of the type just described which further

includes a means for displacing an improperly drilled case with relation to the remaining shell cases so that it may be readily detected and removed.

5 Another object of the invention is the provision of mechanism for feeding the cases to the holding appliances, which mechanism will preferably include a safety device designed to prevent destructive jamming in the event a shell case fails to properly engage the holding member of the turret by which it is to be transferred to the drilling and discharging mechanism.

Another object of the invention is to provide a drilling spindle mounting, by means of which 15 the idle position of the spindle with relation to the work may be very closely regulated to thereby enable the utilization of a minimum exposed drill area and to insure substantially simultaneous engagement of the drills with the shell cases.

20 Another object of the invention is the provision of a structure of this character which may be relatively cheaply and rapidly produced, and which will be efficient in operation and a general improvement in the art.

25 These and other objects I attain by the construction shown in the accompanying drawings, wherein for the purpose of illustration, I have shown a preferred embodiment of my invention and wherein:

30 Figure 1 is a side elevation of a shell case drilling machine constructed in accordance with my invention;

Figure 2 is an elevation of the drilling machine taken from the opposite side thereof;

Figure 6 is a detail view illustrating the means for insuring correct positioning of the turret;

Figure 7 is an enlarged detail sectional view 45 illustrating the relative positions of the turret and ejecting mechanism at the time of engagement of the ejector therewith;

Figure 8 is a view similar to that of Figure 7, but illustrating the shell casings as withdrawn 50 from their supports and being discharged from the machine;

Figure 9 is a view similar to those of Figures 7 and 8 illustrating the method of stopping the machine in the event there is an improperly 55 drilled shell case and of indicating the position

of the improperly drilled shell case to the operator;

Figure 10 is a perspective view illustrating the construction of one of the ejector units;

Figure 11 is an enlarged partial section taken on line 3—3, of Figure 1.

Figure 12 is a base view of a shell case illustrating the position of the flash openings;

Figure 13 is a vertical sectional view through the shell casing of Figure 12 illustrating in solid and dotted lines the positions of the single drill forming the openings therein;

Figure 14 is a vertical sectional view through one of the drill spindle mountings employed; and

Figure 15 is a wiring diagram illustrating the connections employed with the several control switches utilized.

Turret control (Figs. 1 to 3, 5 and 6)

Referring now more particularly to the drawings, numeral 10 generally designates the main frame of the machine which rotatably mounts a turret 11. This turret comprises a body section 12 generally rectangular in formation and provided at its ends with trunnions 13 engaged in bearings 14 on the sides of the frame 10. Intermediate the sides of the frame, the turret body bears a plurality of radially extending brackets 15, each secured at its base to the body 12 and each having associated therewith a plurality of shell case receiving studs 16. The studs 16, as more clearly shown in Figure 11, each comprise a tapered section 17, the smaller free end of which is of considerably less diameter than the mouth or projectile receiving end of the shell case so that it may readily enter the same. Such free ends are furthermore grooved at 18 at the sides thereof which are longitudinally disposed as regards the axis of the turret to provide drill clearance while, at the same time, affording at the outer end of the spindle, a sufficient support for the inner or butt end of the shell case. Each of the brackets 15 furthermore provides a plurality of clamps, one associated with each stud 16 and each comprising a block 19 having a face thereof which confronts the bracket 15 provided with a V-notch 20 and each provided with spring guides 21, the springs of which constantly urge the spring block toward the bracket. The shell case, when applied to the stud by a feeding mechanism, hereinafter to be described, initially engages freely over the stud and through the mouth of the clamp provided by the notched block just described, by reason of the relatively small diameter of the projectile receiving end 22 of the shell case 23. These clamps exert sufficient pressure upon the shell case to prevent any rotation thereof during the step-by-step motion which is imparted to the turret or by the drilling operation.

In the present illustration, the turret is shown as provided with four brackets and as operating through four station positions which may be designated as the loading position L, the drilling position D, the extracting position E and the idle position I. It will, of course, be understood that in lieu of the particular number of brackets herein disclosed, the turret might be equipped with any desired number of brackets in which case the idling positions would be arranged to suit the particular design adopted. The mechanism for controlling the operation of the turret comprises a main shaft 24 driven through a reduction gear 25 by a motor 26. The shaft 24 through

gear 27 and pinion 28 drives the shaft 29, upon which is mounted an eccentric gear 30, meshing with a similarly eccentric gear 31 mounted on a cross shaft 32. The cross shaft 32 mounts the control disc 33 of a Geneva movement 34, which movement controls the step-by-step rotation of the turret 11. To insure accurate positioning of the turret at each of its stations, one of the trunnions of the turret has mounted thereon a plate 35 having in its periphery a series of notches 36 adapted for the reception of a plunger 37 mounted in suitable guides 38 secured to the frame 10. Movement of this plunger in one direction is controlled by a spring 39, while its movement in the opposite direction, in which it is withdrawn from the notches 36 to permit rotation of the turret, is controlled by a bell crank 40, one arm of which engages the plunger and the other arm of which engages a cam 41 secured to shaft 32.

Drilling spindles and the controls therefor (Figs 1 to 3, 5 and 14)

Mounted upon the frame 10 at opposite sides thereof and slightly rearwardly of the turret axis are a pair of standards 42, the forward faces of which support a horizontal guide 43 upon which is mounted the slide 44, which in turn mounts bearing brackets 45 of a plurality of drill spindles 46. The guides for drill spindles 46, which are more particularly shown in Figure 14, each comprise upper and lower arms 47 and 48 mounting bearings 49 for the spindle 50. The lower end of each spindle comprises the usual chuck 51 for drill 52, there being one spindle and its mounted drill for each stud of the respective turret brackets. The spindle is urged upwardly by a spring 53 and the upper end of the spindle is provided with a bearing mounted cap 54. The bearings 49 of the spindle are preferably lubricated by arranging a lubricant container 55 at the upper end of the bracket and connecting the same by a port 56 to the upper end of the upper bearing 49, from which bearing the lubricant is conducted, by a port 57, to and through the lower bearing 49 and finally to a collection outlet, generally designated at 57a. The standards 42 additionally support a transverse rock-shaft 58 having a tappet arm 59 for each drill spindle 50. The flared outer ends of these arms swivel blocks 60 through which are adjustably directed the threaded stems 61 of the tappets proper. These tappets have an enlarged and flattened head 62 at the lower ends which engages against the upper surface of the cap 54 of the upper end of the associated drill spindle and serve as a means for adjusting the vertical limit of movement of the associated drill spindle. In order that elevation of a given spindle may be insured even though the spring 53 of one or more of the spindles fail, means are provided to prevent any but a very limited separation of the cap and the associated tappet, this means being at present disclosed as comprising clips 63 secured to the cap and having angular upper ends overlying the upper surfaces of the enlarged heads of the tappets. The rock-shaft 58 is actuated through an arm 64 secured thereto and engaging through a follower the periphery of a cam 66 secured to shaft 29.

The slide 44 is actuated through a cam 67 secured to shaft 32 at the right-hand side of the machine, this cam being more clearly shown in Figures 2 and 11. This cam is arranged to hold the slide in one position during the initial portion of the stay of a given bracket of the turret

at the drilling station D, during which period the cam 66 initially acts to depress the drilling spindles and form an opening at one side of the base of the percussion cap recess 68 of the shell case 23. The drill spindles are then permitted to elevate, following which the cam 67 shifts the slide to the left in Figure 11. Following which the drill spindles are again depressed to form the second opening in the drill case. The spacing of these openings may obviously be regulated by the configuration of cam 66. Cam 66 is provided with a relatively short depression 69 which provides for elevation of the drills during shifting of the slide 44 and with a second elongated depression 70 which provides for elevation of the drills during the advance of the turret from one station to another.

The spindles 46 are driven by a spindle motor 71, which through a belt 72 drives a shaft 73 mounted upon the upper ends of a pair of standards 74 at the rear of the machine. This shaft 73 mounts individual pulleys 75 for each spindle and belts 76 trained about idlers are led to pulleys 78 upon the individual spindles. Idlers 77, one for each belt 76 are mounted on individual slides 79, providing for individual tensioning of the belts.

Extractor mechanism (Figs. 7-10)

Supported by the sides of the frame 10, on guides 80 is a slide 81 reciprocated in timed relation to the turret movements by means of an eccentric 82 mounted on shaft 29. This eccentric through link 83 engages a rock-arm 84 bearing a segment 85 engaging a rack on the under surface of slide 81. Mounted on slide 81 are a plurality of extractor heads 86, an individual example of which is shown in Figure 10. Each extractor head comprises a block 87 preferably rectangular in form and having a stem 88 extended through and secured to a crossbar 89 of slide 81. Each head includes at least one pivoted lever 90 which is spring positioned by spring 91 to engage its grappling beak 92 in the extractor groove 93 of a shell case mounted upon an opposed stud 16 of a bracket which is disposed in the extractor position E. When a bracket of the turret arrives in the extractor position, the control mechanism advances slide 81 bringing the extractor levers 90 into position to engage the shell case and immediately prior to the next advancing step of the turret, the slide 81 is moved rearwardly, carrying with it the drilled shell cases. After a predetermined rearward movement of the slide the rear ends of levers 90 are engaged by a trip 94 which depresses the same, thereby releasing the shell cases and permitting the same to fall to a discharge chute 95, as more clearly shown in Figures 7 and 8.

As pointed out hereinbefore, due to the small size of the drills employed and further to the nature of the materials (brass and bronze alloys), breakage of drills of the small diameters necessary may occur at any movement. Thus, in a practical machine of the character under discussion, it becomes necessary to provide a means for detecting the presence of any improperly drilled case. To provide such a means, I mount in each of the extractor heads a spring pressed plunger 96, forward movement of which is urged by a spring 97 and limited by a plate 98. This plunger has at its forward end a pair of feeler prongs 99, positioned for extension through the openings formed in the aligned shell case by drill 52. In event one or more of these openings

has not been formed or has been incompletely formed, the plunger is moved rearwardly through engagement of the feeler point with the base of the shell. The plunger has a rearwardly extending stem 100 which, when the plunger is moved rearwardly, engages with a plate 101 moving the same against the action of the spring 102 to cause actuation of a micro-switch 103. Under these circumstances, the micro-switch 103 is opened thereby instituting opening of the circuit of the motor 26 and at a given time stopping the machine.

Since the plunger 99 of the improperly drilled shell case will exert a spring pressure against the base of the improperly drilled shell at a point radially spaced from the point at which the extractor grips it, this shell will be "cocked" out of line with the shells which have been properly drilled and which will be still held by the extractors due to the fact that stoppage occurs prior to engagement of levers 90 with the tripping element 94 and after the cases have cleared the studs by reason of the conclusion of a timer hereinafter more fully described. The operator may accordingly readily detect the improperly drilled shell and remove the same before again starting the machine. With starting of the machine the properly drilled shells will be dropped into the chute and the operation of the machine will proceed normally.

By reason of the use of feeler prongs 99, it becomes necessary to insure stripping of the shells from the extractor mechanism, for after the release of the grappling beaks 92 the shells might otherwise remain on these feeler prongs. For this reason, I mount upon the slide 81 for shifting movement in a direction longitudinal to the machine a stripping plate 104. This plate has its movement limited through a slot and pin engagement as at 104a and may be held in a retracted position by means of springs 104b. It is pointed out, however, that the springs 104b may be omitted, since the stripping plate will be advanced upon the slide 81 by the pins of the slot and pin engagement at 104a during retraction of the slide and as the slide is advanced will engage the heads of the shell cases and thereby be retracted upon the slide. This plate has at its forward edge a series of down-bent fingers 104c projecting between adjacent extractor heads 86 for engagement with diametrically opposite portions of the shell base. As the slide moves rearwardly in the extracting operation and the pivoted levers are tripped by trip 94, the rear edge 55 of this slide engages against stops 104d, carried by the machine frame, so that the down-bent fingers 104c are caused to extend beyond the front faces of the heads 86 and completely disengage the shell from the feeler fingers.

It may, of course, happen that a normally drilled shell may, through some failure, pass the extractor mechanism and remain on the stud through the idler position of the turret. Under these conditions, if the shell continued to remain in position until the bracket of which the stud formed a portion was at the loading position, serious damage to the machine might occur. I accordingly arranged between the extracting position and the loading position, a detector generally designated at 105. This comprises a hinged plate 105a, so arranged as to clear the turret mechanism, per se, but to be disposed in the path of a shell case carried by any of the studs of a bracket of the turret. If engaged by a shell case, which the extractor has failed to remove,

this plate will actuate a switch 106 thereby stopping the machine.

It will, of course, be understood that any of the safety devices employed in stopping a machine described hereinbefore or hereinafter, may include in its circuit a tell-tale 107 through which the operator may be apprised of the particular switch which has caused the stoppage and accordingly apprised of the portion of the machine at which the error causing the stoppage may be corrected.

Loading mechanism

The loading mechanism, more particularly shown in Figures 5 and 5A, comprises a magazine 108 which through vertical partition walls 109 is subdivided into a plurality of chambers corresponding in number and spacing to the spindles of the individual station brackets of the turret, such chambers being adapted for the reception of a stack of shell cases 23. At the bottom of each chamber the side walls are inwardly curved as at 109a to provide a slotted bottom, as more clearly shown in the section forming Figure 5A, and the front and rear walls of the magazine are terminated slightly above the bottom thereof. Mounted for reciprocation beneath the magazine is a feeding plate 110 which is connected to slide 81 as at 111 for simultaneous movement therewith. This plate mounts pushers 112, one for each of the chambers of the magazine and aligned with the slot 113 at the bottom thereof. As the plate 110, during an extracting operation by the extractor mechanism carried by slide 81, is moved to the left in Figure 5, these pusher plates 112 engage the lowermost shell in the magazine chamber and force the same from the rear end of the magazine onto engagement with the aligned stud of the turret. Arranged adjacent the pusher plates is a safety switch 114 which is controlled by a hinged plate 115 arranged adjacent the forward edges of pusher plates 112 and held in contact therewith by a spring 116. The pusher plates 112 are connected to the feeding plate 110 by shear pins 117 and in the event any jamming occurs, such as might result from accidental entrance to the magazine of foreign matter, these pins will shear enabling the affected pusher plate 112 to shift the detector plate 115 and cause operation of the switch thereby stopping the machine.

It will be obvious that in order to accomplish the visual indication of an improperly drilled shell hereinbefore described and illustrated in Figure 9, it will be necessary that the ejector mechanism be permitted to move rearwardly at least a distance sufficient to enable the shell case to clear the rear ends of the studs from which they are being removed. To this end, I employ a timing switch 118 which, while it might be arranged for operation by any part moving synchronously with the slide 81, is at present disclosed as being arranged beneath the feeding plate 110 and as being controlled by cam 119 secured to this plate. The switch 118 is in circuit with the detector switch and is normally open and the cam 119 will not close switch 118 until the plate 110 has moved to the left in Figure 5 a distance sufficient to enable the extractor mechanisms to disengage the shell cases from the studs of the bracket at the extractor station. At this time, the cam 119 will close switch 118 and in the event switch 103 has been closed, the circuit to the motor 26 will be broken and operation of the machine stopped.

Operation

Assuming the machine to be completely stopped with the parts in the positions illustrated in Figure 5 and assuming that all of the shell cases upon the studs 16 to have been properly drilled, switches 103, 106, 114 and 118 are open. The operator first closes the starting switch 120 of the drill operating motor 71. This switch closes the starting circuit S-71 for the motor operating solenoid switch 121 and thereby closing both the motor circuit of motor 71 and a holding circuit H-71 for switch 121. The completion of the circuit of motor 71 prepares a circuit 122 for main motor 26. The operator then closes switch 123, which through solenoid switch 124 completes the circuit to the main motor 26, which as illustrated in the diagram forming the Figure 15, is preferably of that type having solenoid release brake 125, the release of which occurs simultaneously with the completion of the circuit to the motor. The solenoid switch 124 for motor 26 completes a holding circuit H-26 for the circuit of the motor 26. This holding circuit includes a normally closed solenoid operated switch 126, the circuit of the actuating coil of which is completed by closure of either switches 106 or 114 or by the simultaneous closing of switches 103 and 118. The main motor having been started, the initial operation from the position illustrated in Figure 5 is that of shifting the shell cases upon the studs at station E from their studs with simultaneous application of fresh shell cases to the studs at station L. Assuming that there is no jamming of the newly supplied shell cases at the station L, this operation will be completed and the drilled shell cases from the extractor station E will be discharged into the chute 95. If a jam occurs at the loading station, switch 114 will be closed and switch 126 opened thereby breaking the circuit to the main motor 26 through opening of the holding circuit of switch 124 controlling the same. Assuming that an extractor has failed to remove a shell case and that the same has passed through the station I, this shell case upon engagement with plate 105 will open switch 103 of detector 104 thereby completing the circuit of switch 126 and stopping motor 26.

Again let it be assumed that of the shell cases upon the studs at station E, one has been improperly drilled due to drill breakage or some other cause. In this case, the extractor which engages this particular shell has during the movement of the slide 81 to the position illustrated in Figure 5 brought its feeler prongs 99 into engagement with the improperly drilled surface of the defective shell with the result that switch 103 is closed. This will not, at this time, cause stoppage of the machine due to the fact that switch 118 is open. When, however, continued operation of the main motor has shifted the slide 81 to the left for a short distance thereby moving with it the feed plate 119, cam 119 will close switch 118 thereby completing the circuit to the switch 126 and stopping motor 26. It will be noted that completion of any of the safety stop circuits will render it impossible to again close the circuit of motor 26 except under "jogging" control, such as may be necessary to position the parts in order that the fault causing stoppage may be eliminated. By utilization of signals 107 in the individual safety switch circuits, the presence of the fault may be readily detected and cured.

Since the construction illustrated is obviously

capable of considerable modification without departing from the spirit of my invention, I do not wish to be understood as limiting myself thereto except as hereinafter claimed.

I claim:

1. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable extractor for each holder and adapted to engage the drilled article at a point spaced from the opening drilled therein and withdraw it from the holder and a yieldable feeler associated with each extractor and adapted to enter the drilled opening of the article, said feelers and extractors acting to support the articles when completely extracted from the holders and to provide differing supported positions for properly and improperly drilled articles.

2. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable extractor for each holder and adapted to engage the drilled article at a point spaced from the opening drilled therein and withdraw it from the holder and a yieldable feeler associated with each extractor and adapted to enter the drilled opening of the article, said feelers and extractors acting to support the articles when completely extracted from the holders and to provide differing supported positions for properly and improperly drilled articles, means to release the extracted articles and means to prevent operation of said releasing means if any of the extracted articles is improperly drilled.

3. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable slide, an extractor for each holder carried by the slide and adapted to engage the drilled article at a point spaced from the opening drilled therein and withdraw it from the holder, a yieldable feeler associated with each extractor and adapted to enter the drilled opening of the article, said feelers and extractors acting to support the articles when completely extracted from the holders and to provide differing supported positions for properly and improperly drilled articles, and means operated by reciprocation of the slide for releasing said extractors and disengaging the articles from said feelers.

4. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable slide, an extractor for each holder carried by the slide and adapted to engage the drilled article at a point spaced from the opening drilled therein and withdraw it from

the holder, a yieldable feeler associated with each extractor and adapted to enter the drilled opening of the article, said feelers and extractors acting to support the articles when completely extracted from the holders and to provide differing supported positions for properly and improperly drilled articles, and means to prevent operation of said releasing and disengaging means if any of the articles are improperly drilled.

5. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable slide, an extractor for each holder carried by the slide and adapted to engage the drilled article at a point spaced from the opening drilled therein and withdraw it from the holder, a yieldable feeler associated with each extractor and adapted to enter the drilled opening of the article, said feelers and extractors acting to support the articles when completely extracted from the holders and to provide differing supported positions for properly and improperly drilled articles, means to check reciprocation of the slide operation of which is initiated by engagement of a feeler with an improperly drilled article and means to prevent operation of the last named means until the articles are completely disengaged from the holders.

6. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable extractor for each holder and adapted to engage the drilled article at a point spaced from the opening drilled therein and withdraw it from the holder and a yieldable feeler associated with each extractor and adapted to enter the drilled opening of the article, said feelers and extractors acting to support the articles when completely extracted from the holders and to provide differing supported positions for properly and improperly drilled articles, means to release the extracted articles and means to prevent operation of said releasing means if any of the extracted articles is improperly drilled, comprising electrical means to check reciprocation of said extractors and a circuit for said electrical means closed by engagement of a feeler with an improperly drilled article.

7. An extractor mechanism for drilling machines having a rotatable turret provided with axial rows of holders for articles to be drilled and means for imparting a step by step rotation to the turret to successively aline said holder rows with the extractor mechanism after drilling of articles held thereby, said extractor mechanism comprising a reciprocable slide, an extractor for each holder carried by the slide and adapted to engage the drilled article at a point spaced from the opening drilled therein and withdraw it from the holder, a yieldable feeler associated with each extractor and adapted to enter the drilled opening of the article, said feelers and extractors acting to support the articles when completely extracted from the holders and to provide differing supported positions for properly and improperly drilled articles, and electrical means to prevent operation of said releasing and disengag-

ing means if any of the articles are improperly drilled, including a switch carried by the slide and operated by engagement of a feeler with an improperly drilled article.

8. An extractor mechanism for drilling machines having a rotatable turret provided with axial rows of holders for articles to be drilled and means for imparting a step by step rotation to the turret to successively align said holder rows with the extractor mechanism after drilling of articles held thereby, said extractor mechanism comprising a reciprocable slide, an extractor for each holder carried by the slide and adapted to engage the drilled article at a point spaced from the opening drilled therein and withdraw it from

the holder, a yieldable feeler associated with each extractor and adapted to enter the drilled opening of the article, said feelers and extractors acting to support the articles when completely extracted from the holders and to provide differing supported positions for properly and improperly drilled articles, electrical means to check reciprocation of the slide comprising an open circuit closure of which is initiated by engagement of a feeler with an improperly drilled article and timing means to prevent closure of the circuit until the articles are completely disengaged from the holders.

ERNEST A. OAKES.
